UNITED STATES PATENT OFFICE.

JAMES E. BURDETT, OF CLAREMONT, NEW HAMPSHIRE, ASSIGNOR OF ONE-HALF TO
JOHN T. DWYER, OF CLAREMONT, NEW HAMPSHIRE.

NECKTIE-PRESSER.

1,102,569.

Specification of Letters Patent.

Patented July 7, 1914.

Application filed September 12, 1913. Serial No. 789,560.

To all whom it may concern:

Be it known that I, JAMES E. BURDETT, a citizen of the United States, residing at Claremont, in the county of Sullivan, State 5 of New Hampshire, have invented certain new and useful Improvements in Necktie Pressers; and I do hereby declare the following to be a full, clear, and exact description of the invention, such as will enable 10 others skilled in the art to which it appertains to make and use the same.

This invention relates to certain novel and useful improvements in necktie pressers and has particular application to an article 15 adapted especially for pressing and stretching string neckties, four-in-hands and the like.

As is well known, after a necktie has been worn two or three times, it becomes rumpled 20 and creased so that it presents a very untidy appearance, and it is frequently a matter of inconvenience, especially to travelers, to have the tie pressed when it is desired to wear the same. It is my purpose in the 25 present instance to provide an exceedingly simple, compact and efficient form of press by means of which one or more ties may be stretched and pressed so that all creases and wrinkles will be removed therefrom. I 30 also aim to provide a pressing device which is composed of relatively few parts so that it may be manufactured and marketed at a relatively low cost.

With the above recited objects and others 35 of a similar nature in view, my invention consists in the construction, combination and arrangement of parts set forth in and falling within the scope of the appended claims.

40 In the accompanying drawings, Figure 1 is a plan view of a necktie presser or stretcher embodying my invention, a tie stretched thereon being indicated in dotted lines. Fig. 2 is a transverse sectional view 45 taken on the line 2—2 of Fig. 1. Fig. 3 is a detail view of the clamping bar. Fig. 4 is a vertical sectional view on the line 4—4 of Fig. 1.

In the present instance I have shown my 50 invention as embodied in a tie presser or stretcher which is designed for use in pressing at least two ties, but I wish it to be understood of course that the proportions of the device may be varied so that any de-

sired number of ties may be accommodated 55 thereby.

Referring now to the accompanying drawing in detail, the letter A indicates as an entirety the frame of the device which is preferably made of a single piece of wire 60 bent into rectangular form and comprising the side bars 1—1 and the top bar 2 which is provided with the inwardly bent or bowed portions 3—3 separated by the outwardly bowed central portion 4. The meeting ends 65 of the wire which form the lower portion or bottom of the frame are indicated by the numeral 6—6 and are connected by the coupling sleeve 5, the portions of the wire above the meeting ends being bent to form the 70 compound loops 7—7. Extending transversely of the central portion of the frame and connected at its ends to the side bars thereon is the bar 8, which is preferably formed of two strands of wire separated 75 so that the tie B may be run therethrough if desired.

The numeral 10 designates the retaining closed loop bar which is designed to fit over and slide on the side members of the frame, 80 said bar being movable along the frame in the manner readily understood, and after the tie has been wrapped or stretched upon the frame this bar may be shifted over the same to firmly bind the tie and hold the 85 same against displacement.

From the above description taken in connection with the accompanying drawing, the construction and manner of employing my invention will be readily understood. 90 One manner in which it may be used is shown in the drawing. In applying the tie for the purpose of stretching the same, one end of the tie is slipped through one of the compound loops forming a part of the bottom bar of the frame, and the tie is then carried upward over the alining depressed portion of the top bar, thence down between the members of the central transverse bar, thence around the compound loop of the 95 bottom bar and thence up over the depressed portion of the top bar again, and so on until the tie is completely wrapped or stretched on the frame. The retaining loop bar is then shifted over the tie and along the 100 side members of the frame to securely bind the tie upon the presser. It will thus be seen that when the tie is stretched upon the 105

latter it may be drawn as taut as desired to remove any wrinkles or creases in the latter and at the same time will be held securely in position so that it will not be drawn off, no matter what tension is applied to the same. I have described one manner in which the tie may be wrapped or stretched upon the device, but it will of course be understood that this may be varied to suit the individual requirements. As stated, a number of ties may be wrapped upon the frame and they may be removed therefrom one at a time as required.

What I claim is:

- 15 1. A device of the class described comprising a frame member provided with a holding loop at one side thereof, and a depression formed in the opposite side of the frame, a central bar extending across the frame and a sliding retaining bar for binding a tie upon the frame.
- 20 2. A device of the class described comprising a frame formed of a single piece of wire bent into approximately rectangular form, the lower side of the frame having a depressed portion, a central bar extending transversely between the side members of the frame, and a sliding retaining loop movable

upon the side members of the frame for holding the tie stretched upon the frame.

30

3. A device of the class described comprising a wire frame including a transverse top bar, a transverse bottom bar provided with a compound retaining loop and a sliding loop bar movable over the side members of the frame and adapted to bind a tie upon said frame.

4. A device of the class described comprising a frame formed from a single piece of wire bent into approximately rectangular form, the meeting end of the wire at the lower side of the frame being connected by a sleeve, said wire at the lower side being bent to form a plurality of retaining loops, a transversely extending double bar connected to the side members of the frame, the top of the frame being bent to provide depressed sections separated by an outwardly bowed portion, and a sliding tie retaining member carried by the frame.
